UNITED STATES PATENT OFFICE

JOSEPH S. BENNETT, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

AIR-COOLED FURNACE WALL

Application filed January 24, 1928. Serial No. 249,121.

My invention relates to furnaces, and it has for one object the provision of means, whereby the loss of heat due to radiation from boiler walls may be reduced to a negligible value and the efficiency of the furnace thereby increased.

Another object of my invention is to provide means, whereby the infiltration of air into the furnace may be very greatly minimized.

A further object of my invention is to provide an air circulating system, whereby the heated air may be removed from above the boilers of the furnace.

A still further object of my invention is to provide a simple and efficient system, whereby preheated air may be supplied to the wind box of a stoker,—the system contemplating the drawing of the heated air from the region above the boilers down over the exposed side walls of the furnace. Experience has shown that the preheating effected by this method is just the proper amount resulting in the removal of the moisture from the coal and expediting combustion in that portion of the furnace where ignition is about to take place. Since the preheating is not too great, there is no need for special protection for the exposed furnace parts. Hence, the air is preheated to just the proper extent without the use of expensive preheaters.

Other objects and applications of my invention, as well as details of construction and operation, will be apparent more fully hereinafter, when taken in connection with the accompanying drawings, wherein

Fig. 1 is a vertical sectional view of a furnace embodying my invention;

Fig. 2 is a transverse sectional view taken on the line 2—2 of Fig. 1;

Fig. 3 is a side elevational view of the structure of Fig. 1 from the outside of the furnace;

Fig. 4 is an enlarged, detail, horizontal sectional view taken on the line 4—4 of Fig. 2;

Fig. 5 is a side elevational view of the structure of Fig. 4, and

Figs. 6 and 7 are detail sectional views of the secondary wall taken on the lines 6—6 and 7—7, respectively, of Fig. 5.

Referring to the drawings, a furnace 1, which is positioned in a boiler room 2, having a main floor 3 and a ceiling 4, comprises a stoker 5 which extends rearwardly from a front wall 6 in the direction of a rear wall 7. The stoker terminates in an ash pocket 8 at the base of which is a pair of rotary grinders 9. Access may be had to the stoker portion of the furnace through an opening 11.

The furnace 1 further comprises a pair of brick side walls 12—12. These walls extend vertically upwardly and, in combination with the walls 6 and 7, form a setting for a boiler system 13. For purpose of illustration, a sterling-type boiler system has been shown comprising a lower drum 14 and upper drums 15, 16 and 17 which are respectively interconnected with the drum 14 by groups of pipes 18, 19 and 21. The upper drums 15, 16 and 17 may be suitably supported and are protected by a covering 22 which extends over the entire upper end of the boiler setting, completely enclosing the same.

In the course of the operation of the furnace 1, considerable heated air accumulates in a region 23 which is positioned between the upper covering 22 of the furnace and the ceiling 4 of the boiler room 2. The general practice, heretofore, has been to remove this heat by providing open windows through which the heated air may escape to the outside of the boiler room 2. Thus, there is considerable energy lost. This loss is prevented in the practice of my invention as will presently appear.

A second loss in the boiler systems of the prior art is that due to heat radiation through the walls of the furnace. In accordance with my invention, this loss also is eliminated, and air is supplied to a desired portion 24 of the fuel bed at just the proper temperature. The above-noted desired results are accomplished in the manner shown in the drawings, wherein a pair of secondary side walls 25—25 are spaced from outer sides 26—26 of the main side walls 12—12, so as to form air chambers or ducts 27. In order to simplify the description, one of the secondary side walls and its associated air passage

only is hereinafter described in detail. This secondary wall 25 may be extended upwardly from the floor 3 of the boiler room 2 to a point 28 adjacent to an upper end 29 of the boiler setting 1, as shown particularly in Fig. 2. A front portion of the air chamber 27 is closed by an end wall 31, while a rear portion is closed by an end wall 32. The bottom portion of the chamber 27 may be closed by the floor 3 of the boiler room, while the upper portion 33 is entirely open, so that air in the region 23 may be drawn into the chamber 27 as will be explained hereinafter. The secondary wall 25 may comprise a plurality of vertically extending supporting members 34 (Figs. 4, 5 and 6) and a plurality of horizontal supporting members 35 (Figs. 5 and 7). The vertical members 34 may comprise a pair of angles 36 and 37, flanges 38 and 39 of which are positioned back-to-back with flanges 41 and 42 forming supporting shoulders. A panel section 40 of desired heat-resisting material may be positioned between the flanged portion 39 of one vertical angle and the flange portion 38 of a second vertical angle spaced therefrom, rearward movement being prevented by the flange portions 37 and 36 thereof. Each of the horizontal members 35, which serve to support further one of the panel sections 40 in any desired vertical position on the spaced vertical members 34 comprises a pair of angles 41, flanges 42 and 43 of which are positioned in abutting relation, so that flange 42 engages a lower edge of one panel section and flange 43 engages an upper edge of a lower panel section. The remaining flanges 44 and 45 engage the rear sides of the two adjacent panel sections. An outward movement of the panel 40 away from the flanges 36, 37 and 44, 45 may be prevented by vertical and horizontal angle sections 46 and 47 respectively. As shown in Figs. 4 to 7, inclusive, the angles 46 and 47 are detachably secured in position by bolts or in any other desired manner, so that the panel 40 may be readily removed in the event that it is desired to have access to the adjacent portion of the furnace wall. Such construction, therefore, permits any desired portion of the furnace wall to be reached without destroying or removing the whole of the secondary wall 25. A similar secondary wall may be provided for the front and rear walls 6 and 7, respectively, but this has not been illustrated in order to simplify the description of the invention.

The rear end wall 32 of the air chamber 27 is provided with an opening 48 which is positioned approximately midway between the floor 3 and the top of the furnace, and it is connected by a duct 49 to one side 50 of a suction fan 51. An opposite side of the suction fan 51 is similarly connected to the other air duct 27. A discharge conduit system 52

leading from the fan 51 opens into an air box 53 positioned directly below the stoker 5, whereby the air passing from said air box may be forced through the stoker into the fuel bed 24.

When the fan 51 is actuated, heated air is withdrawn from the portion 23 of the boiler room 2 and caused to pass through the air ducts 27-27 over the outer side 26 of the furnace side walls 25-25, thereby absorbing the heat radiating therefrom. The already heated air is thus further preheated, and experience has shown that the final temperature of the air as it passes through the ducts 49 is just the proper value to obtain the best results in the furnace 1. Since the preheating is not too great, there is no need for special protection for the stoker and parts in contact with the heated air passing out of the wind box 53. It is also noted that the desired amount of preheating is obtained without the use of added equipment, and that the simplicity and cheapness of construction of the preheating system enables it to be applied to existing furnace installations at a moderate cost.

A further feature of my invention is the provision of means, whereby the air may be caused to traverse a circuitous path through the air ducts 27, 27 over the outer face 26 of the walls 12-12, the velocity of the air being increased over a portion 54 of the furnace side walls 12-12, which is heated to the highest temperature. To this end, I provide in each of the air ducts 27 a deflecting plate 55 which extends forwardly and downwardly between the primary and secondary walls 12 and 25 from an upper rear edge portion 56 of the air duct 27. As shown in Fig. 1, the structure 55 terminates at a point 57, which is disposed in spaced relation to the furnace front wall 1 and to the fuel bed 24, and which is immediately adjacent to the hottest portion 54 of the furnace side walls 12-12. The effect of the structure 55 on the heated air currents through the conduits 27, 27 is shown by the dot-and-dash lines of Fig. 1.

Assuming the presence of a heated fuel bed 24 and the operation of the fan 51, air in the region 23 between the upper end of the furnace and the boiler room ceiling 4 becomes very hot. The heated air in the region 23 is drawn into the air ducts 27-27 by the fan 51 and caused to pass over the outer sides 26-26 of the furnace walls 12-12 in the direction shown by the arrows in Figs. 1 and 3, the velocity of the heated air over the hottest portion 54 of the furnace walls 12-12 being increased so as to permit a greater absorption of the heat from this portion of the furnace walls. When the air reaches the discharge outlets 27, it has become preheated to just the desired extent and the air is now withdrawn through the conduits 48 and discharged from the fan 51 through

the conduit system 52 and air box 53 into the portion of the furnace below the stoker 5, thereby facilitating combustion conditions in the fuel bed, particularly that portion 24 where ignition is about to take place. Thus, the efficiency of the furnace is very greatly increased, since radiation losses through the furnace side walls 12-12, as well as from that portion 15, 16 and 17 of the boiler system which is in the upper part of the furnace, are substantially eliminated. Moreover, the ventilation of the power plant as a whole is very greatly assisted.

It is noted that the foregoing side wall air ducts causes the substantial elimination of a third furnace loss, namely, that due to the infiltration or leakage of air into the furnace through the brick work of the walls. This loss sometimes is a very serious one, since the additional air entering the combustion chamber is sufficiently great to cause a large decrease in the efficiency of combustion. The positioning of the air ducts 27, 27 on the outside of the furnace walls, provides a seal, wherein a negative pressure is maintained by the suction effect of the fan which is equal to or greater than the negative pressure in the furnace.

While I have shown only one form of embodiment of my invention, for the purpose of describing the same and illustrating its principles of construction and operation, it is apparent that various changes and modifications may be made therein without departing from the spirit of my invention. For example, the fan 51 may be positioned above the furnace and caused to force, rather than draw, air through the ducts 27. I desire, therefore, that only such limitations shall be imposed thereon as are demanded by the prior art.

I claim:

1. A furnace comprising a stoker, a side wall extending upwardly from said stoker, a boiler system having one part thereof positioned in the upper portion of the furnace, a wall spaced from the exposed side of said side wall to form an air passage, one portion of said side wall being heated to a greater extent than the other portions thereof, means whereby air may be drawn through said air passage over said exposed side of the furnace wall, and means positioned in said passage whereby the velocity of the air passing over said first-mentioned portion of said side wall may be increased.

2. A furnace installation comprising a fuel supporting portion, a pair of side walls, certain portions of which are heated to a greater extent than other portions, secondary walls positioned in spaced relation to said side walls, respectively, to form air ducts, means whereby the heated air at the upper portion of said furnace may be drawn through said air ducts and thereafter sup-

plied to said furnace, and means whereby the velocity of the air passing through said ducts may be increased over said first-mentioned portions of said side walls.

3. A furnace comprising a support for a fuel bed, a boiler system associated therewith, walls surrounding said fuel support and the boiler system and constituting the main walls of the furnace, a supplemental wall spaced apart from said main wall and terminating adjacent the top of the furnace to afford thereat an opening to the space between said walls substantially coextensive with the width of said supplemental wall, said supplemental wall being composed of detachable panels affording access to the main wall, a blower connected with the lower portion of the space between said main and supplemental walls and adapted to evacuate said space whereby air above the furnace is drawn downwardly into said space, and a duct connecting said blower with the space below the fuel support whereby the heated air drawn from above the furnace between the main and supplemental walls is supplied to the furnace for combustion purposes.

4. A furnace comprising a support for a fuel bed, a boiler system associated therewith, walls surrounding said fuel support and the boiler system and constituting the main walls of the furnace, a supplemental wall spaced apart from said main wall and terminating adjacent the top of the furnace to afford thereat an opening to the space between said walls substantially coextensive with the width of said supplemental wall, said supplemental wall being composed of detachable panels affording access to the main wall, a blower connected with the lower portion of the space between said main and supplemental walls and adapted to evacuate said space whereby air above the furnace is drawn downwardly into said space, a duct connecting said blower with the space below the fuel support whereby the heated air drawn from above the furnace between the main and supplemental walls is supplied to the furnace for combustion purposes, and baffle elements between the main and supplemental walls arranged to afford restrictions increasing the velocity of the air over given portions of the surfaces of the main walls.

5. A furnace installation comprising main walls constituting a mount for a boiler system, a support for a fuel bed established within said walls, a supplemental wall spaced apart from said main walls and terminating adjacent the top of the furnace, a blower connected with the lower portion of the space between said walls and adapted to evacuate said space whereby heated air above the furnace is drawn downwardly into said space, a duct connecting the blower with the space immediately below the fuel bed support, and

baffle means between the said walls forming a restriction in the air channel at a point immediately adjacent the space above said fuel bed support whereby air drawn between the walls is accelerated in its movement past the hotter portions of the main walls.

5 6. A furnace installation comprising a stoker, a boiler positioned above said stoker, walls enclosing said boiler and stoker, said walls comprising a refractory portion and a relatively thin portion spaced outwardly therefrom to form an air duct extending continuously and uninterruptedly from the top of the boiler to the bottom of said installation, the last named wall portion being formed of a series of detachable panels affording access to the inner wall portion, and means for drawing air into said duct at the top from the space above the boiler and feeding it into the furnace beneath the stoker, said walls preventing infiltration of air therethrough into the furnace.

10 7. A furnace installation comprising a stoker, a boiler and a hollow wall housing said stoker and boiler, said wall comprising a relatively thick refractory inner portion and a relatively thin paneled outer portion in spaced relation thereto, the space between said wall portions constituting an air duct extending continuously from the top to the bottom of said installation, and means for drawing air into said duct from the space above the said installation and for subsequently forcing the heated air into the furnace beneath the stoker.
